PIERCE MASON TRAVIS, OF RIDGEWOOD, NEW JERSEY, ASSIGNOR TO TRAVIS PROCESS CORPORATION, OF JERSEY CITY, NEW JERSEY, A CORPORATION OF DELAWARE

PROCESS OF REMOVING AMORPHOUS WAX FROM PETROLEUM OILS

Application filed July 16, 1927. Serial No. 206,332.

This invention relates to improvements in treating petroleum oils and fractions thereof, containing amorphous paraffine wax to effect the removal of the wax therefrom while in the amorphous state. The process of the invention is of special value and application in the treatment of petroleum oils containing lubricating oil constituents and amorphous wax and provides a simple and economical process adapted to remove the amorphous wax continuously without a preliminary treatment that might impair the lubricating properties of the oil.

In refining petroleum oils for the production of high grade lubricants it is customary to distil off the lighter fractions, such as the gasoline, kerosene, etc., with steam or at reduced pressure to avoid cracking of the lubricating oil constituents as cracking reduces the viscosity of the lubricating oil constituents and materially decreases their value. Crude oil reduced in this manner contains amorphous wax which tends to congeal at low temperatures and its presence is therefore objectionable in a lubricating oil because of the high pour test it gives to the oil. It is impossible from a practical standpoint to remove the wax while in an amorphous state from oils of this character in the ordinary filter press due to rapid plugging of the filtering medium. In order to convert the amorphous wax to a crystalline form so that it might be satisfactorily removed by filter pressing a high temperature must be employed which is such as to greatly impair the lubricating properties of the oil.

It has been customary in the past to blend oils of this character with a diluent such as naphtha, chill the blend to an extremely low temperature and allow the naphtha-oil solution to stand for a period of several days to permit the wax to settle during which time the entire body of oil must be maintained at a temperature of about -10° F. to 0° F. This treatment, known as cold settling, requires large storage capacity and an excessive amount of refrigeration.

Attempts have been made to effect the separation of amorphous wax from oils of this

character by centrifugal action but such operations in the past have been of a very limited capacity due to the small capacity of the machines it was found necessary to employ and to the difficulties encountered in removing the separated wax from the zone of centrifugal action.

The present invention provides an improved process for separating amorphous wax from petroleum oils containing it which is adapted to be carried out continuously in large scale refining operations. According to the present invention the oil to be treated is blended with a diluent such as naphtha; the mixture heated to a temperature of approximately 100° F. and thoroughly agitated to insure all of the wax present passing into solution in the diluent. The mixture is then gradually cooled in the presence of a finely divided solid gathering medium to a temperature of about -10° F. and slowly agitated during the chilling operation. The naphtha serves to maintain the mixture in a fluid state at the extremely low temperature employed and to decrease the density of the naphtha-oil solution. The minute particles of solid gathering medium serve as nuclei to which the wax adheres. The density of the mixture of the solid gathering medium and wax adhering thereto is increased by the presence of the gathering medium. The chilled oil is then subjected to centrifugal pressure to effect separation of the wax and solid gathering medium from the chilled oil and the mixture of wax and solid gathering medium is mechanically discharged in a continuous manner from the zone of centrifugal action at one point with movement toward the axis of rotation while the solution of wax free oil and blending naphtha is discharged continuously therefrom in similar manner at another point.

The blending naphtha may be subsequently separated from the wax free oil by distillation and recovered for further use as a diluent.

The solid gathering medium may be separated from the wax mixture by heating and allowing the solid material to settle from the melted wax or the solid material may be con-

tinuously separated from the melted wax by a further centrifuging treatment.

The process of the invention has the advantage that by providing for the positive mechanical removal of heavy solid material from the zone of centrifugal action a light blending naptha and a relatively heavy solid gathering medium may be employed to create a comparatively wide margin between the density of the solution of the oil in the blending agent and that of the mixture of the gathering medium and adherent wax so that a lower centrifugal pressure may be employed to secure the separation of the wax and oil.

The process of the invention will be further described in connection with the accompanying drawings which illustrate in a somewhat conventional manner one form of apparatus adapted for the practice of the improved process of the invention, but it is intended and will be understood that this further description is for the purpose of exemplification and that the invention is not limited thereto.

In the drawings:

Fig. 1 is a somewhat diagrammatic representation in elevation of an arrangement of apparatus adapted for the practice of the improved process of the invention.

Fig. 2 is an elevation partly in section of one form of centrifuge suitable for use in the arrangement illustrated in Fig. 1.

Fig. 1 of the drawings shows a storage tank 1 connected through pump 2 and line 3 with a heat insulated mixing tank 4 having a heating coil 5 and stirring device 6 arranged therein. The mixing tank 4 is also provided with a valved inlet connection 7 for the introduction of a diluent material such as a naptha distillate. Storage bin 8 is arranged so that a finely divided solid material may be supplied therefrom to the mixing tank 4 through connection 9 as desired. Valved draw-off connection 10 and pump 11 are arranged to withdraw liquid from the mixing tank 4 and convey it to the insulated cooling tank 12 provided with coil 13 through which a suitable cooling medium may be circulated. Cooling tank 12 is also equipped with a mechanical stirring device 14. Connections 15, 16 and pump 17 are arranged to supply cooled oil from the cooling tank 12 to a centrifuge 18. Valved connection 15 may advantageously be provided to withdraw oil from the upper portion of the cooling tank 12. A stand pipe 19 is interposed in connection 16 to assist in maintaining a constant rate of feed to the centrifuge. Connection 20 is provided to convey the effluent liquid from the centrifuge to a storage tank 21. The cold clear solution discharged from the centrifuge may if desired be passed in heat exchanging relations with the fresh oil supplied to the cooling tank 12 before it is

finally discharged to the storage tank. Connection 22 is arranged to direct solid material discharged from the centrifuge to the conveyor 23.

The centrifuge illustrated in Fig. 2 comprises a bowl 24 supported by the supporting web 25 and rotatably mounted on the shaft 26. The element 27 is keyed to the shaft 26 and is provided at its outer surface with extension 28, which is helical in form and extends approximately to the inner surface of the bowl 24. The central portion of the bowl 24 is cylindrical in form tapering toward the shaft at one end. The other end of the bowl is provided with a ring 29 extending inwardly from the periphery of the bowl. The tapered end of the bowl is continued until it approaches nearer to the shaft 26 than the inner edge of the ring 29. The bowl 24 is provided with a series of openings 30 around its periphery at one end beyond the ring 29. The shaft 26 extends through a gear casing 31 and may be driven directly from any suitable source of power, for example, by a silent chain engaging the sprocket 32. The bowl 24 and the supporting web 25 are driven by a collar 33 from the shaft 26 through a set of differential gears in the gear casing 31 so arranged that the bowl 24 rotates in the same direction as the helix 28 but at a slightly lower speed. While both the bowl 24 and the helix 28 rotate at high speed the differential between them is relatively small so that any difficulties incident to the provision and care of a high speed bearing between the shaft 26 and collar 33 are eliminated. The direction and speed of rotation of the helix 28 relative to that of the bowl 24 is such that the helix will operate to discharge continuously at the tapered end of the bowl any solid material which would otherwise accumulate therein, for example, the bowl may be driven at 1000 to 1200 R. P. M. and the helix at 1050 to 1250 R. P. M. Collecting rings 34 and 35 are provided at opposite ends of the bowl to collect the wax free naptha-oil solution and separated solid material as they are discharged from the bowl. A stuffing box 36 is arranged to prevent leakage of the material introduced through the interior of the hollow shaft 26.

In the operation of the apparatus described and illustrated in accordance with the improved process of the invention the oil to be treated for the removal of amorphous wax, which has preferably been subjected to a preliminary treatment, for example, to treatment with 66 Bé. sulphuric acid or filtering to remove asphaltic constituents which act as protective colloids tending to prevent the adherence of wax particles to a solid gathering medium is supplied to the mixing tank 4 from the storage tank 1 and a diluent, such as naptha added to the oil as desired. The most ad-

vantageous proportions of oil and diluent material will vary somewhat with the character of the oil and diluent material employed. A blend comprising 40% of the oil to be treated and 60% of a closely cut naptha having an end boiling point of approximately 430° F. will produce satisfactory results in most cases. The naptha-oil mixture is then heated to a temperature of about 100° F. and thoroughly agitated. A small amount of finely divided solid material, such as diatomaceous earth is then introduced to the mixing tank 4 from the storage bin 8 and thoroughly mixed with the naptha-oil solution by the mechanical stirring device 6. The quantity of gathering medium to be employed will vary with the wax content of the oil. About 1% by weight of 200-300 mesh fuller's earth will usually be sufficient to effect satisfactory separation of the wax from the naptha-oil solution. The mixture is then chilled in the cooler 12 to a temperature of -10 to 0° F. by circulating a cooling medium such as calcium chloride through the cooling coil 13. During the cooling operation the mixture should be mildly agitated at intervals to secure uniform cooling and maintain the dispersion of the solid gathering medium throughout the solution. The cooled oil is pumped to the stand pipe 19 from which it is supplied to centrifuge 18 in a continuous manner. The mixture entering the centrifuge through the shaft 26 passes through the hollow element 27 and is discharged to the interior of the rotating bowl through a series of openings 37 where it is subjected to centrifugal pressure to which the mixture subjected is many times greater than the force of gravity and causes the gathering medium and adherent wax to separate from the naptha-oil solution forming an outer layer which is mechanically conveyed to the tapered end of the bowl by the helix 28 where it is discharged from the bowl continuously. The motion of the helix relative to the bowl is not sufficient to act positively on the liquid, due to its greater fluidity, so that the inner layer of cold clear liquid will flow through the bowl axially in a direction opposite to the motion of the outer layer of solid material, passing over the inner edge of the ring 29 as it is displaced by fresh oil supplied to the bowl. As the gathering medium and adhered wax is mechanically conveyed by the helix 28 to a point nearer the axis of rotation while still subjected to the action of centrifugal force than the point at which the naptha-oil solution is discharged, the last traces of the oil or solution may be separated therefrom so that a maximum yield of wax free oil and a higher melting point wax may be obtained. The speed at which the bowl may most advantageously be driven will vary somewhat with the character of the oil, the rate at which the oil is introduced thereto, the length of the bowl

and the amount of solid gathering agent employed. In general, a lower speed is required with a longer bowl and an increased amount of gathering agent. With a bowl 24" in diameter and 30" long a rotative speed of 1000 R. P. M. will in most cases be sufficient to effect satisfactory separation of the gathering medium and adherent wax from a naptha-oil solution continuously supplied thereto at a rate of 3000 to 4000 gallons per hour.

Where a refinery has a plant equipped for the old gravity method of cold settling, the process of the invention may be employed in conjunction therewith. For example, the cooled solution may be allowed to stand for a time before centrifuging to effect a preliminary concentration of the gathering medium and adherent wax by settling. A layer of cool clear solution may then be drawn off from the upper part of the settled liquid body and the remainder of the solution containing the wax and solid material concentrated therein centrifugally treated as above described.

In refineries which are not provided with the equipment for present day cold settling methods the various oils or solutions now subjected to the cold settling method of treating may be treated continuously in accordance with the present invention while avoiding heavy investment in cold settling tanks and excessive refrigerating capacity. The process of the invention has the further advantages that the apparatus required is of rugged construction and does not require critical adjustment or the supervision of a skilled operator.

I claim:

1. The improvement in the treatment of petroleum oils for the removal of amorphous wax contained therein, comprising chilling the oil to be treated in the presence of a finely divided solid material and a low boiling diluent and subjecting the chilled mixture to centrifugal force whereby the wax and finely divided solid material and the wax free oil and diluent are separated into layers, continuously discharging the wax and admixed solid material from the zone in which it is subjected to centrifugal force at one point with movement toward the axis of rotation, and continuously discharging the wax free oil and diluent material from said zone with movement toward the axis of rotation at another point.

2. The improvement in the treatment of petroleum oils for the removal of amorphous wax contained therein, comprising chilling the oil to be treated in the presence of a finely divided solid material and subjecting the chilled mixture to centrifugal force whereby the wax and admixed finely divided solid material and the wax free oil are separated into layers, continuously discharging the wax and admixed solid material from the zone

in which it is subjected to centrifugal force at one point with movement toward the axis of rotation, and continuously discharging the wax free oil from said zone with movement toward the axis of rotation at another point.

5 3. The improvement in the treatment of petroleum oils for the removal of amorphous wax contained therein, comprising chilling the oil to be treated in the presence of a finely divided solid material and a low boiling naptha and subjecting the chilled mixture to centrifugal force whereby the wax and finely divided solid material and the wax free oil and naptha are separated into layers, continuously discharging the wax and admixed solid material from the zone in which it is subjected to centrifugal force at one point with movement toward the axis of rotation, and continuously discharging the wax free oil and naptha from said zone with movement toward the axis of rotation at another point.

10 4. The improvement in the treatment of petroleum oils for the removal of amorphous wax contained therein, comprising chilling the oil to be treated in the presence of a finely divided solid material and subjecting the chilled mixture to centrifugal force whereby the wax and admixed finely divided solid material and the wax free oil are separated into layers, causing the wax and admixed solid material to move axially in the zone in which they are subjected to centrifugal force and causing the wax free oil to move axially in said zone in the opposite direction, continuously discharging the wax and admixed solid material from the zone in which it is subjected to centrifugal force at one point with movement toward the axis of rotation, and continuously discharging the wax free oil from said zone with movement toward the axis of rotation at another point.

15 5. The improvement in the treatment of petroleum oils for the removal of amorphous wax contained therein, comprising heating the oil to be treated in the presence of a low boiling diluent and subsequently chilling the admixed oil and diluent in the presence of a finely divided solid material, subjecting the chilled mixture to centrifugal force whereby the wax and finely divided solid material and the wax free oil and diluent are separated into layers, continuously discharging the wax and admixed solid material from the zone in which it is subjected to centrifugal force at one point with movement toward the axis of rotation, and continuously discharging the wax free oil and diluent from said zone with movement toward the axis of rotation at another point.

20 6. The improvement in the treatment of petroleum oils for the removal of amorphous wax contained therein, comprising heating the oil to be treated in the presence of a low boiling naptha distillate and subsequently chilling the admixed oil and naptha in the

presence of a finely divided solid material, subjecting the chilled mixture to centrifugal force whereby the wax and finely divided solid material and the wax free oil and naptha are separated into layers, continuously discharging the wax and admixed solid material from the zone in which it is subjected to centrifugal force at one point with movement toward the axis of rotation, and continuously discharging the wax free oil and naptha from said zone with movement toward the axis of rotation at another point.

25 7. The improvement in the treatment of petroleum oils for the removal of amorphous wax contained therein, comprising chilling the oil to be treated in the presence of a finely divided solid material and a low boiling diluent, reducing the temperature of the mixture to below 0° F., subjecting a body of the chilled mixture to a settling operation, subsequently drawing off a layer of clear liquid from the upper portion of said body, withdrawing a concentrated mixture from the lower portion of said body and subjecting the mixture so withdrawn to centrifugal force whereby the wax and finely divided solid material and the wax free oil and diluent are separated into layers, continuously discharging the wax and admixed solid material from the zone in which it is subjected to centrifugal force at one point with movement toward the axis of rotation, and continuously discharging the wax free oil and diluent material from said zone with movement toward the axis of rotation at another point.

30 In testimony whereof I affix my signature.
PIERCE MASON TRAVIS.
